HEMSTITCH SEWING-MACHINE.

No. 833,277.

Specification of Letters Patent.

Patented Oct. 16, 1906.

Application filed April 26, 1905. Serial No. 257,452.

To all whom it may concern:

Be it known that I, CHARLES MACKENZIE ABERCROMBIE, a citizen of the United States, residing at Bridgeport, in the county of Fairfield and State of Connecticut, have invented a certain new and useful Improvement in Hemstitch Sewing-Machines, of which the following is a full, clear, and exact description.

10 This invention relates to hemstitch sewing-machines; and its object is to provide a simple and practical mechanism for locating the several lock-stitches forming the hemstitch figure by giving to the needle-carrier, in addition to its vertical movements, lateral movements in directions transverse to each other.

In the common construction of hemstitch sewing-machines it has been the general practice to give to the needle-carrier the usual vertical movements for the formation of the lock-stitch and lateral movements transverse to the line of feed of the material for placing the individual lock-strokes on and off the hem-fold, coupled with means for feeding the material two stitches forward and one backward. This feeding mechanism is complicated, heavy of operation, and hard to control in its limit of feed movements and involves a nicety in construction and also an adjustment of parts hard to maintain and without which the open-work of a hemstitch figure is liable to be imperfect, owing to the threads of the material not being properly drawn into the stitch.

35 In the present construction a four-motion feed is employed to advance the material two feed movements for the formation of each hemstitch figure, and the needle-carrier is mounted in an oscillatory frame pivoted to the overhanging arm and controlled to effect lateral movements of the needle transverse to and in line with the feed.

In the accompanying drawings, illustrating the invention, in the several figures of which like parts are similarly designated, Figure 1 is a front elevation with a portion of the bed-plate and overhanging arm in section. Fig. 2 is an end elevation, partly in section. Fig. 3 is a front elevation, partly broken away to better illustrate the mechanism for transmitting motion to the loop-taker. Fig. 4 is a transverse section through the overhanging arm, taken substantially on the line A B, Fig.

1, illustrating the cam action for controlling the lateral movements of the needle in line 55 with the hemstitch seam. Fig. 5 is a transverse section of the bed-plate and lower main shaft, illustrating the action of the feed-lift cam and its connections for giving vertical movements to the feed-dog. Fig. 6 is a front 60 elevation of the universal joint employed to permit transverse lateral movements of the needle-carrier. Fig. 7 is a diagram of the work, showing the position of the needle punctures for the formation of a hemstitch seam, 65 together with the position of the needle-thread before it is drawn to position, by the action of the take-up, to form the open-work, the material of the hem-fold being shown as of coarse weave. Fig. 8 is a diagram of the 70 work as it appears after the stitches of the hem-fold have been drawn to form the open-work in the hemstitch. Fig. 9 is a development of the cam-groove for controlling the lateral movements of the needle-carrier in the 75 direction of the line of the seam.

1 is the bed-plate of the sewing-machine; 2, the overhanging arm; 3, the band-wheel; 4, the needle-actuating shaft; 5, the quartering-crank connections for operatively connecting the needle-actuating shaft 4 with the lower main shaft 6.

7 is the loop-taker, 8 the loop-taker shaft. (Shown in dotted lines, Figs. 2 and 3.)

9 is the bracket secured by screws 10 to the 85 bed-plate 1 and in which the loop-taker shaft 8 is journaled.

11 is a counter-shaft provided with a bevel-gear 12, and 13 is a bevel-gear fast on shaft 8, and through these gears motion is transmitted 90 to the loop-taker.

14 is a gear secured on shaft 11 and meshing with a gear 15, secured on shaft 6, such gears being of the proportion of two to one, thus giving to the loop-taker two revolutions 95 to one complete actuation of the needle for the formation of the lock-stitch.

16 and 17 are collars secured by screws 18 and 19, respectively, to shafts 6 and 11, respectively, to prevent end thrust of said 100 shafts.

20, 21, and 22 are suitable screws for securing the gears 12, 14, and 15, respectively, to the shafts 6 and 11, respectively. To the forward end of the needle-actuating shaft 4 105 is suitably secured a take-up cam 23, to

which latter is fulcrumed, by a suitable stud 24 (shown in dotted lines, Fig. 1) and nut 25, a link 26, the opposite end of which is connected to the needle-carrying bar 27 by a suitable connection, as 28. In suitable bearings 29 and 30 is mounted the usual presser-bar 31, provided between its bearings with the usual presser-spring 32, presser-bar-lifting collar 33, and tension-releasing bracket 34, its lower end 35 provided with a cloth-presser 36, such as is common to the Wheeler & Wilson hemstitch sewing-machine.

37 is a presser-lifter lever secured to the overhanging arm by a screw 38, and 39 is a take-up lever mounted and operated in the usual manner. Suitably mounted on the face-plate 40 is a thread-leader 41, thread-check 42, and tension mechanism 43.

44 is the feed-controlling lever operatively connected, by a suitable connection, as 45, to an adjustable lever 46, the end 47 of which is journaled to a lever made integral with the rock-shaft 48, the opposite end of said lever 46 being provided with a suitable slide-block 49, adjustable on the lever 50, which lever in turn is secured to a shaft 51, mounted in a suitable bearing 52, (see Fig. 1,) formed integral with the bed-plate of the sewing-machine, said shaft 51 being provided at its opposite end with a lever 53, stud 54, and roller 55, which roller co-operates with a cam-groove 56, formed in the cam 57, which cam is provided at its periphery with gear-teeth 58, which mesh with the teeth of a gear-wheel 59, secured to the lower shaft 6, (see Fig. 5,) such gears being in the proportion of three to one, thus effecting one rotation of the cam to three rotations of the shaft 6.

60 is a cam (see Figs. 1 and 4) mounted to rotate upon a bearing 61, (shown in dotted lines, Fig. 4,) made integral with a stud 62, which latter is secured in the overhanging arm by a nut 63 and provided with an opening 64, through which passes the needle-actuating shaft 4. The cam 60 is held against movement lengthwise of its bearing 61 by a screw 65, tapped into said bearing, the said screw overlapping the face of the hub 66 of the cam 60. Motion is transmitted to the cam 60 through the bevel-gear 67, secured, by screws 68, to the needle-actuating shaft 4, the teeth of the gear 67 meshing with the gear-teeth 69, formed on the rear side of the cam 60, the proportion of such gears being as three to one, the same as the proportion of the coacting gear-teeth formed on the cam 57 and gear 59, which latter cam and gear control the backward and forward movements of the feed-dog, while the former gear 67 and cam 60 control the lateral movements of the needle.

70 is a rock-lever provided with a shaft 71, which latter is journaled in a suitable bearing 72, formed on the under side of the overhanging arm 2, said shaft being provided with a

hub 73 and collar 74 to hold it against lengthwise movement. The free end of the rock-lever 70 is provided with a roller-stud 75 and roller 76, which latter travels in a cam-groove 77, formed in the face of the cam 60, the opposite end of the rock-lever 70 being provided with a groove 78, into which is adjustably secured, by a suitable bolt 79 and nut 80, one end of an adjustable connection 81, the opposite end of said connection being secured, by a suitable stud-screw 82, to a needle-bar-carrying frame 83, which frame is mounted to swing laterally in directions transverse to each other. In the outer end of the overhanging arm 2 is journaled a shaft 84, which shaft is held against lengthwise movement by a collar 85, provided with a set-screw 86, the opposite end of said shaft 84 constructed with oppositely-arranged bearings 87 87, in which is journaled a short rock-shaft 88, provided with an opening 89, in which is secured, by a screw 90, one end of a connecting-rod 91, the opposite end of said rod being secured by screws 92 in the upper end of the needle-bar-carrying frame 83. The rock-lever 70, connection 81, needle-bar-carrying frame 83, and the connection comprising parts 84 to 92, inclusive, comprise a line of connections for operatively connecting the cam 60 with the needle-bar-carrying frame 83 for giving to the needle lateral movements transverse to the lengthwise feed of the material, the parts 84 to 92, inclusive, forming a universal-joint connection between the needle-bar-carrying frame 83 and overhanging arm 2 for permitting the needle to be moved laterally in transverse directions.

The mechanism for effecting the lateral movements of the needle in opposite directions in line with the feed of the material comprises suitable bearings 93, formed in the under side of the overhanging arm, in which is mounted a shaft 94, to the forward end of which is secured a lever 95, which lever at its free end is provided with a slot 96, into which projects a lug 97, formed integral with the frame 83, and to the opposite end of said shaft 94 is secured, by a screw 98, a rock-lever 99, the free end of which is provided with a roller-stud 100 and roller 101, which latter tracks in a groove 102, formed in the periphery of the cam 60, which cam-groove, in connection with a spring to be hereinafter described, effects a rocking motion of the lever 99, shaft 94, and lever 95, and consequently effects (through the connection comprising the groove 96 and lug 97) lateral movements of the frame 83 in opposite directions in line with the feed of the material.

The lever 99 is provided with an arm 103, which extends backward (see Fig. 4) in a direction transverse to the axis of the shaft 94, and said arm 103 has an adjusting-screw 104, which in the operation of the machine abuts against a step 105, formed on the overhanging

arm 2, and to more securely hold said screw against accidental adjustment is provided a jam-nut 106. To the forward end of the arm 2 is secured one end of a spring 107, Fig. 5 2, its opposite end being attached to the frame 83, which spring when free to act holds the frame 83 in its rearward position and in doing so holds the point of the adjusting-screw 104 in contact with the step 105, so that the roller 101 is held at a greater or less distance from the wall 108 of the cam-groove 102. The wall 109 of the cam-groove does not influence the travel of the roller 101, owing to the spring 107 holding the roller 101 15 in the direction of the wall 108 to the desired adjustment of the adjusting-screw 104. By these means the throw of the lever 99 may be varied in accordance with the character of work to be done.

110 is a feed-dog (see Fig. 5) secured by screws 111 to a feed-bar 112, which feed-bar is fulcrumed, by a stud 113 and nut 114, to a lever 115, which is secured by screw 116 to the forward end of the feed rock-shaft 48, 25 mounted in any usual way underneath the bed-plate 1 of the sewing-machine, thus connecting the feed-dog 110, through the adjustable lever 46, Fig. 2, lever 50, shaft 51, lever 53, stud 54 and roller 55, with the cam-groove 30 56, which latter controls the backward and forward movements of the feed-dog.

117 is a set-screw for securing the gear 59 to the shaft 6.

The cam 57 is mounted upon a shaft 118, 35 journaled in a bearing formed in the bracket 119, Figs. 1 and 5, which latter is secured to the under side of the bed-plate 1 by screws 120. To effect vertical movements of the feed-dog 110, is secured by a suitable screw, 40 as 121, upon the end of the shaft 118, a feed-lift cam 122, formed with cam portions 123, which coact with the roller 124, mounted upon a roller-stud 125, secured in a lever 126, fast on the rock-shaft 127, which rock-shaft is held between pintles 128, threaded into lugs 129, formed integral with the bed-plate 1 of the sewing-machine, such pintles being held against accidental adjustment by screws 130. Formed integral with the rock-shaft 127 is a lever 131, the free end of which carries a slide-block 132, held in position by a stud 133 and nut 134; said block working in a slot 135, formed in the end of the feed-dog-carrying bar 112, thus effecting through the action of the cam 122 vertical movements of the feed-dog 110.

The operation of the device is as follows: Supposing the needle-bar to be at its highest throw ready to descend to form the lock-stitch *a*, (see Fig. 7,) the roller 76 of the rock-lever 70 would be riding the concentric portion 136 of the cam 60 and the roller 101 of the rock-lever 99 would be held by spring 107 in contact with the wall 137 of the cam 60, 65 the roller 55, carried by the stud 54, occupying

ing the position 138 in the cam-groove 56, the roller 124, operatively connected with the rock-shaft 127, riding one of the cam portions 123 and being held in contact with the cam 122 by the pressure of the presser-foot 36, 70 through the action of spring 32, acting upon the upper surface of the feed-dog 110, which through connection 131 and shaft 127 holds the lever 126 so as to effect the coöperation of the roller 124 and cam 122. As the needle 75 descends through the cloth in the formation of the stitch *a* the roller 76 of the rock-lever 70 travels from the position 136 of the cam-groove 77 to the concentric portion 140 of said cam-groove, giving to the needle-carrying bar a slight lateral movement to the right, the roller 101 continuing to ride the wall 137 of the cam-groove 102 in the periphery of the cam 60, the roller 55, carried by the lever 53, traveling from the position 138 of the cam-groove 56 to the position 141 of the cam-groove 56, the roller 124 passing from one of the cam portions 123 to one of the concentric portions 142 of the cam 122, thus through the action of the roller 124 passing from the 80 cam portion 123 to the concentric portion 142, allowing the feed-dog 110 to be moved downward by the action of spring 32, encircling the presser-bar 31, and the travel of the roller 55 from the position 138 to 141, through 85 the connections 46, 50, rock-shaft 51, feed rock-shaft 48, and feed-dog-carrying bar 112, causing the feed-dog 110 to be moved toward the operator in position to be later moved upward and forward to advance the material. 90 As the needle rises in the formation of stitch *a* the roller 76, carried by the rock-lever 70, travels from the position 140 to the position 143 in the cam-groove 77, thus moving the needle laterally to the left ready to descend for the formation of stitch *b*, and roller 55 from position 141 to the position 144, causing 95 the feed-dog 110, through connections 46, 50, 51, 48, and feed-dog-carrying bar 112, to be moved forward, thus effecting a feed movement of the material from *a* to *b*, the roller 124 having passed during this time from one of the concentric portions 142 to one of the cam portions 123, thus forcing the feed-dog 110 upward into contact with the material, 100 while the roller 55 in its travel from position 141 to 144 causes the feed-dog to be moved to effect a feed movement of the material, the roller 101, carried by the rock-lever 99, traveling from wall 137 to wall 145 in the cam-groove 102, thus giving to the needle a slight lateral movement in line with the seam and toward the operator. In the descent of the needle to form the stitch *b* the roller 76, carried by the rock-lever 70, tracks the cam-groove 77 to the position 146 and in doing so causes the needle to be moved laterally to the right while in the material, so as to properly present the loop of needle-thread to the loop-taker and at the same time force an opening 105 110 115 120 125 130

in the material which, in connection with the succeeding stitch, forms the open-work of the hemstitch - seam. During the downward stroke of the needle in the formation of stitch *b* the roller 101 continues to ride the wall 145 of the cam-groove 102, the roller 55 traversing the groove 56 of the cam 57 from the position 144 to the position 147, which portion of the cam-groove is concentric with the axis of the cam, and consequently leaves the feed-dog in its advanced position; but during this time the roller 124 travels from one of the high portions 123 of the cam 122 to the concentric portion 142, thus permitting the feed-dog 110 to drop to its lowest position ready for its return movement. During the upward stroke of the needle-bar incident to the formation of stitch *b* the roller 76, carried by the rock-lever 70, travels from the position 146 to the position 148, causing a slight lateral movement of the needle-bar to the left, the roller 101 having passed the wall 145 of the cam-groove 102 and being held a slight distance from the wall 108 by the point of the adjusting-screw 104 being brought in contact, through spring 107, with step 105, thus giving to the needle-bar a slight lateral movement in line with the seam and in the direction of the feed, the roller 55 during this time having traveled from position 147 in the cam-groove 56 to the position 149, and in doing so moved, through connections 46, 50, 51, 48, and 112, the feed-dog 110 back toward the operator or in position to be again moved to advance the material under the needle, the roller 124 continuing to ride one of the concentric portions 142 of the cam 122. In the descent of the needle to form stitch *c* the roller 76 travels from the position 146 to the position 150, completing the lateral movement of the needle-bar to the left, so as to bring it in line with stitch *c* before the point of the needle enters the material, and while the needle is completing its downward stroke the action of the cam-groove 77 on roller 76 of rock-lever 70 moves the needle to the right, thereby forming an opening in the material and at the same time presenting the needle-thread loop to the action of the loop-taker, the roller 101 continuing its travel in the groove 102 opposite the wall 108, the roller 55 traveling from the position 149 of the cam-groove 56 to the position 151 and the roller 124 continuing to travel one of the concentric portions 142 of the cam 122. As the needle-bar rises out of the material in the formation of stitch *c* the roller 76 travels from the position 150 in the cam-groove 77 to the position 136, or to the position which the needle-bar occupied when commencing the hemstitch figure, the roller 101 traversing the groove 102 from a position adjacent to the wall 108 to the wall 137 and in doing so giving to the needle a slight lateral movement in line with the seam and in a direction opposite to the feed of the material, the

roller 55 tracking the cam-groove 56 of the cam 57 from the position 151 to 138, effecting, through the connections 46 50 51 48 112 and the feed-dog 110, the second feed movement of the material, and the roller 124 traveling from one of the concentric portions 142 of the cam 122 to one of the cam portions 123, thus completing the hemstitch figure by the employment of a one-way feed of the material in combination with a needle-carrier having lateral movements in directions transverse to each other.

From the foregoing it will be understood that while the needle is in the goods for the formation of each of the stitches *b* and *c* the needle is given a lateral movement to the right, so as to displace the threads of the material parallel with the seam toward the hem fold *d*, and when the needle rises from the stitch *c* and the take-up is actuated in connection with the formation of stitch *c*, the threads of the material having been previously displaced toward the hem fold, the pull of the take-up causes the threads of the material lying transverse to the line of feed and the stitches *b* and *c* to be drawn to the position *e*, Fig. 8, thus forming the open-work of the seam, as illustrated by *fff*.

It is not essential that the lateral movements of the needle and the feed of the material shall occur during the exact time herein pointed out relative to the vertical movements of the needle, for such lateral movements of the needle as occur when the needle is out of the material may take place at any time while the needle is above the material, and the same is true of the feed movements; but it is desirable to time the machine so that the lateral movements of the needle and the feed movements of the material occur at substantially the time previously pointed out. Further, it will be understood that the two forward feed movements occur, first, between stitches *a* and *b* and, second, between stitches *c* and *a'* and that while the needle is out of the material between stitches *a* and *b* there is a lateral movement of the needle-bar to the left to bring the needle in line with stitches *c* and *b* and a slight lateral movement of the needle-bar toward the operator, and after the needle has entered the material the needle is moved to the right to present the thread-loop to the point of the loop-taker, and between stitches *b* and *c* there is a lateral movement of the needle parallel with and in the direction of the feed of the material and also slightly to the left to position the needle for the formation of stitch *c*, and after the needle has entered the material in the formation of stitch *c* the needle is given a lateral movement to the right, as in the formation of stitch *b*, to present the thread-loop to the action of the loop-taker. Between stitches *c* and *a'* the needle is given a lateral movement to the right to bring it in line with

stitch *a* and at the same time a very slight lateral movement toward the operator. This completes the first hemstitch figure, and the several succeeding hemstitch figures are made by similar movements of the needle and feed, and the second hemstitch figure would be represented by *a' b' c' a'* in the order mentioned, the stitch *c'* being made alongside of the stitch *b*. The third hemstitch figure would be represented by *a² b² c² a³*, the stitch *c²* being made alongside of the stitch *b²*, and the fourth hemstitch figure would be represented by *a³ b³ c³*, the stitch *c³* being made alongside of the stitch *b²* and then the other stitch to the right.

It is to be observed that the control of the lateral movements of the needle in transverse directions is entirely independent of the control of the movements of the feed-dog for advancing the material to the action of the needle, and therefore if such needle actuation were used in connection with a four-motion feed actuated to advance the material for each successive lock-stitch, as is common to the ordinary sewing-machine, supposing the first stitch to be made at *a*, the second and third stitches would be interlocked at *b*, as the needle would be moved backward at the same time that the material was fed backward, thus effecting two stitches at *b*. The fourth stitch would be located at *a²* and the fifth and sixth stitches at *b²*, and so on, forming a seam of two interlocking stitches off the hem fold and one single stitch on the hem fold. Hence it is evident that the invention is capable of additional applications of a needle controlled to move laterally in transverse directions.

The invention is not limited to the details hereinbefore described, since it is evident that these may be varied within a wide range, while employing substantially the same principle, and this reservation applies equally well to embodiment of the principle of the invention in other sewing-machines than those designed specially for hemstitching.

What I claim is—

1. In a sewing-machine, cloth-feeding mechanism, and stitch-forming mechanism, the latter including a needle-bar-carrying frame jointed to its support and capable of oscillation in the line of the cloth-feed and also transversely to such feed to form stitches.

2. In a sewing-machine, the combination of a stitch-forming mechanism including a needle-carrier, a cloth-feeding mechanism, and means to control these mechanisms to give to the needle lateral movements in transverse directions to form stitches.

3. In a sewing-machine, the combination of means for effecting a one-way feed of the material, with a needle-carrier and means to control it to give to the needle lateral

movements in transverse directions to form 65 stitches.

4. In a hemstitch sewing-machine, a stitch-forming mechanism embodying a loop-taker, an eye-pointed needle, a needle-bar, a needle-bar-carrying frame, a needle-actuating shaft, and connections between said shaft and frame for giving to said frame oscillatory movements in transverse directions, in combination with a cloth-feeding mechanism and means to control it to effect two feed movements of the material for each hemstitch figure. 75

5. In a hemstitch sewing-machine, an overhanging arm, a needle, a reciprocating needle-bar, and a needle-bar-carrying frame, said frame pivoted to the overhanging arm and capable of oscillation in transverse directions, a needle-actuating shaft mounted in said arm, a cam, means to drive it from said shaft, and connections between said cam and frame 80 to effect the oscillatory movements of said frame in transverse directions, in combination with a feeding mechanism and means to control it to effect two feed movements of the material for each hemstitch figure. 85

6. In a hemstitch sewing-machine, a stitch-forming mechanism embodying a loop-taker, an eye-pointed needle, a needle-bar, a needle-bar-carrying frame, a needle-actuating shaft, and connections between said shaft and frame for giving to said frame oscillatory movements in transverse directions, in combination with a feeding mechanism comprising a feed-dog, a lift-cam, a feed-cam, and connections between the feed-cam and feed-dog for controlling the movements of the feed-dog to effect two feed movements of the material for each hemstitch figure. 90 95

7. In a hemstitch sewing-machine, a stitch-forming mechanism embodying a loop-taker, a needle, a needle-bar, a needle-bar-carrying frame, a needle-actuating shaft, and connections between said shaft and frame for giving to said frame oscillatory movements in transverse directions, in combination with a main shaft, a feeding mechanism comprising a feed-dog, a lift-cam, a feed-cam, connections between said feed-dog and cams, a shaft upon which said cams are mounted adjacent to the main shaft, and gears of the proportion of three to one connecting said shafts, said lift-cam and feed-cam adapted to control the movements of the feed-dog for effecting two feed movements of the material for each hemstitch figure. 105 110 115

8. In a hemstitch sewing-machine, having an overhanging arm, a needle, a needle-bar and a needle-bar-carrying frame, said frame pivoted to the overhanging arm to oscillate in transverse directions, a needle-actuating shaft mounted in said arm and operatively connected with the needle-bar, a cam mounted adjacent to said shaft, gears operatively 120 125

connecting said shaft and cam and bearing the proportion of three to one and provided with cam-grooves, and connections between the cam-grooves and frame to control the oscillatory movements of the said frame, in combination with a feeding mechanism comprising a feed-dog, a lift-cam, a feed-cam, and connections between the feed-cam and feed-dog for controlling the movements of the feed-dog to effect two feed movements of the material for each hemstitch figure.

9. In a hemstitch sewing-machine, having an overhanging arm, a needle, a needle-bar, and a needle-bar-carrying frame, said frame mounted to oscillate in transverse directions, a needle-actuating shaft mounted in the overhanging arm and operatively connected with the needle-bar, a cam mounted in said arm and geared to said shaft and provided with cam-grooves, and connections between the grooves and frame for effecting control of the oscillatory movements of the needle-bar-carrying frame, in combination with a feeding mechanism comprising a feed-dog, a lift-cam and a feed-cam, said cams mounted upon a shaft adjacent to and operatively connected with the lower main shaft and formed to control, through suitable connections, the movements of the feed-dog for effecting two feed movements of the material for each hemstitch figure.

10. In a hemstitch sewing-machine, having an overhanging arm, a needle, a needle-bar and a needle-bar-carrying frame, said frame pivoted to the overhanging arm and capable of oscillating in transverse directions, a needle-actuating shaft mounted in said arm and operatively connected with the needle-bar, a cam mounted adjacent to and operatively connected with said shaft by gears of the proportion of three to one and provided with cam-grooves which, through suitable connections, control the oscillatory movements of the needle-bar-carrying frame, in combination with a feeding mechanism comprising a feed-dog, a lift-cam and a feed-cam, said cams mounted upon a shaft adjacent to and operatively connected to the lower main shaft by gears of the proportion of three to one, the said lift-cam and feed-cam formed to control, through suitable connections, the movements of the feed-dog for effecting two feed movements of the material for each hemstitch figure.

11. In a sewing-machine, cloth-feeding mechanism, and a stitch-forming mechanism including a loop-taker and a needle-bar-carrying frame, said frame jointed to its support and capable of oscillation in the line of the feed and also transversely to such feed, a transverse movement taking place after the needle has entered the material and while it is presenting its thread-loop to the point of

the loop-taker in the formation of the stitch figure. 65

12. In a sewing-machine, an oscillating needle-bar-carrying frame jointed to its support and capable of movement in transverse directions, a cam, a rock-lever actuated by said cam and connected to said frame to oscillate it transversely to the feed of the material, and a rock-shaft operatively connected with said cam at one end and with the frame at its other end to oscillate said frame in the line of the feed for forming the stitch figure. 75

13. In a sewing-machine, the combination of a needle-actuating shaft, an overhanging arm in which it is mounted, a needle-bar-carrying frame, a jointed support for said frame arranged in the overhanging arm, and a cam arranged in the overhanging arm, and means to rotate it from the needle-actuating shaft, said cam having a face-groove and a peripheral groove, in combination with a rock-lever engaging the face-groove and connected with the needle-bar-carrying frame to oscillate said frame transversely to the line of feed of the material, and a rock-shaft connected with the peripheral groove at one end and having a lever fixed to its other end, said lever engaging the needle-bar-carrying frame to oscillate it in the line of feed of the material. 85

14. In a sewing-machine, the combination of a needle-actuating shaft, an overhanging arm in which it is mounted, a needle-bar-carrying frame, a jointed support for said frame arranged in the overhanging arm, and a cam arranged in the overhanging arm, and means to rotate it from the needle-actuating shaft, 95 said cam having a face-groove and a peripheral groove, in combination with a rock-lever engaging the face-groove and connected with the needle-bar-carrying frame to oscillate said frame transversely to the line of feed of the material, and a rock-shaft connected with the peripheral groove at one end and having a lever fixed to its other end, said lever engaging the needle-bar-carrying frame to oscillate it in the line of feed of the material, said rock-lever having an arm and means to adjust its throw. 105

15. In a sewing-machine, the combination of means for effecting a one-way feed, means to control it to effect two feed movements of the material for the formation of a three-stitch figure, a needle-carrier, and means to control it to give to the needle lateral movements in transverse directions. 115

In testimony whereof I have hereunto set my hand this 24th day of April, A. D. 1905.

CHARLES MACKENZIE ABERCROMBIE.

Witnesses:

E. L. TOLLES,
ABBIE M. DONIHEE.

It is hereby certified that in Letters Patent No. 833,277, granted October 16, 1906, upon the application of Charles Mackenzie Abercrombie, of Bridgeport, Connecticut, for an improvement in "Hemstitch Sewing-Machines," an error occurs in the printed specification requiring correction, as follows: In lines 69 and 71, page 1, the word "of" should read *off*; and that the said Letters Patent should be read with this correction therein that the same may conform to the record of the case in the Patent Office.

Signed and sealed this 30th day of October, A. D., 1906.

[SEAL.]

F. I. ALLEN,

Commissioner of Patents.
